DESIGN FOR AN ASH TRAY OR SIMILAR ARTICLE

Brice L. Jackson, East Orange, N. J.

Application March 14, 1945, Serial No. 118,478

Term of patent 14 years

(Cl. D85—2)

To all whom it may concern:

Be it known that I, Brice L. Jackson, a citizen of the United States and a resident of East Orange, in the county of Essex and State of New Jersey, have invented a new, original, and ornamental Design for an Ash Tray or Similar Article, of which the following is a specification, reference being had to the accompanying drawing, forming part thereof.

Figure 1 is a top plan view of an ash tray showing my new design.

Figure 2 is a side elevational view thereof.

Figure 3 is a bottom plan view of the tray.

Figure 4 is a vertical longitudinal sectional view through the tray on the line 4—4 of Figure 1, and

Figure 5 is an end elevational view of the tray.

I claim:

The ornamental design for an ash tray or similar article, as shown.

BRICE L. JACKSON.
